PASTE APPLYING MACHINE

Paul J. Stefanelli, Washington, D. C.

Application January 23, 1946, Serial No. 642,922

4 Claims. (Cl. 91—33)

1

This invention relates to a paste applying machine and more particularly to a machine for applying paste to wall paper.

An object of this invention is to provide a paste applying machine especially adapted to applying paste to a roll of wall paper as the paper is continuously fed through a series of rollers.

Another object of this invention is to provide a removable reservoir on a paste applying machine of this type.

Still another object of this invention is to provide wipers for the rollers which apply the paste to the paper, whereby a smooth and uniform coat of paste will be applied to one side of the papers.

Still another object of this invention is to provide a machine for applying paste to wall paper having adjustable paper guides so that rolls of various width paper may be used efficiently with this machine.

Yet another object of this invention is to provide a machine of this type which may be produced at a low cost and which may be efficiently maintained with little cost and labor.

In the drawings:

Figure 1 is a top plan view of a machine constructed according to an embodiment of this invention.

Figure 2 is a top plan view with certain parts removed.

Figure 3 is a side view.

Figure 4 is a front end view.

Figure 5 is a rear end view.

Figure 6 is a section view taken on line 6—6 of Figure 1.

Figure 7 is a fragmentary sectional view taken on the line 7—7 of Figure 1.

Figure 8 is a fragmentary sectional view taken on the line 8—8 of Figure 1.

Figure 9 is a fragmentary sectional view taken on the line 9—9 of Figure 3.

Figure 10 is a partial plan view of a wiper.

Figure 11 is a fragmentary sectional view taken on the line 11—11 of Figure 5.

Referring to the drawings the numeral 20 designates generally a frame for this device which consists of a bottom 21, a pair of side walls 22, and a rear end wall 23.

A tank or paste reservoir 24 is mounted on the frame 20 by a wire support 25 fixed to and between the side walls 22. A flat metal angle 30 secures the support 25 to the bottom 21. The tank 24 is formed along its bottom side with a downwardly extending open tubular member 26. The tube 26 may also be adapted to serve as the filler neck for the tank 24 before the tank is placed in the support 25. The tubular member

2

26 is adapted to extend into a rearwardly extending channel 27 of the paste trough 28. The paste from the tank 24 flows into the channel 27 and will be replenished as required by the paste in the tank 24. The trough 28 is supported within the frame by a pair of wire supports 29, which are fixed to the bottom 21 by suitable fastening means 31.

The roll of wall paper 32 is supported above 10 the end wall 23 by a pair of vertical channels 33 fixed to the end of the frame 20, and a rod 34 extending between the channels 33. The rod 34 is pivotally secured to one channel 33 by a pin 35, and engages in an L-shaped slot 36 in the 15 other channel 33. A pair of annular discs 37, adjustable lengthwise of the rod 34 hold the roll of paper 32 from sliding on the rod 34. One disc 37 is loosely mounted on the rod 34 and is kept from sliding in one direction by a sleeve 38 fixed to the rod 34 by a set screw 39. The other disc 37 is formed with a radial slot 40 engageable about the rod 34 and is adjustably fastened to a rod 41, fixed to the end wall 23, by a sleeve 42 20 slideable along the rod 41, and a set screw 43.

25 A paper guide plate 44 is pivotally mounted to the side walls 22 by a pivot at 45 and supported in its normal position by a pair of stop blocks 46 fastened within the frame 20 to the side walls 22. The plate 44 may be pivoted upwardly for 30 access within the frame 20 for cleaning or other purposes. A pair of oppositely disposed laterally adjustable flat angular papers guides 47 are fastened to the plate 44 by a rod 48, fixed to the guide 47, slideable in a sleeve 49, fixed to the plate 44, and is fixed in the sleeve 49 by a set screw 50.

35 A paste applying roller 51 is mounted within the trough 28 by split bearings 52 which are fixed to the side walls 22. The roller 51 is immersed in the paste in the trough 28 and is adapted to transfer paste onto the paper 32. A pair of short 40 wipers 53 are pivoted from the plate 44 at each side and are adapted to wipe the paste from the ends of the roller 51 so the paste will not come up over the edges of the paper. The wipers 53 45 are slidably adjustable along a rod 54 by a sleeve 55 and a set screw 56. The rod 54 is fixed to the plate 44. The wiper 53 is held against the roller by a spring 57 fixed between the arm 58 and the plate 44.

50 A pair of rollers 58 and 59 are mounted on a pivoted section or lever arm 60 of the side walls 22 by bearings 61 and necessary shims as at 62. The sections or levers 60 are pivotally mounted on the side walls 22 by a bar 63 fixed to the sections 60 and pivoted to the wall at 64.

55 The pressure roller 58 is adapted to press the

paper 32 against the roller 51, and the roller 59 is a guide for the paper 32 after it has passed between the rollers 51 and 58 and has been coated with paste.

The roller 58 is formed with narrow annular ribs 65 which press the paper against the roller 51 so that an excess of paste is not applied to the paper. The ribs 65 are made of rubber or other suitable cushioning material.

The guide roller 59 is formed with wider annular ribs 66 also made of rubber or suitable material.

Roller tensioning means are provided for exerting a spring tension between the rollers 51 and 58 and also for holding the pivoted section or levers 60 in place. This tensioning means consists of a hook 67 and eye 68 fixed to the walls 22 and a spring 69 engageable between the hook 67 and the bar 63 fixed to the pivoted section 60. The walls 22 are formed on their upper edge with a concave recess 70 to provide clearance for and a stop for the pivoted section 60.

A wiper 71 is pivotally secured to the sides of the trough 28 and is adapted to engage the lower side of the stretch of paper 32 having paste. The wiper 71 is supported by an arm 72 and is constantly urged into contact with the paper 32 by a spring 73. The wiper 71 is formed with a notched wiping edge 74, so that the paste on the paper is applied smoothly and uniformly throughout its length and width.

In the use and operation of this paste applying machine, a roll of paper upon which the glue is to be applied is slid on the rod 34 and the rod 34 is then moved back into horizontal position as shown in the drawings, where it is locked in the opening 36. The levers 60, bearing the rollers 58 and 59, are pivoted to their open position and the paper is trained between the guides 47 and underneath the rollers 58 and 48. The arms 60 are pivoted back to their operative position where they are locked by the spring-pressed hook 67 engaging in the eye 68. The guide members 47 are adjusted longitudinally of the frame 20 on the plate 44 to hold the paper from lateral movement on the machine. The disks 37 are moved along the length of the rod 34 for abutting the ends of the roll of paper and are locked in place. The disks 37 hold the roll of paper against lateral movement on the shaft 34.

A receptacle 24 containing paste, is inverted in the support 25 so that the neck 26 of the reservoir will engage in the channel 27 for supplying glue into the trough 28. The spring 69 yieldingly urges the roller 58 into engagement with the glue applying roller. The ribs 65 on the roller 58 are provided for pressing the paper between the roller 58 and the glue applying roller at spaced intervals along the length of the rollers so that an excess of glue is not applied to the paper, inasmuch as the pressure is applied only at spaced sections along the width of the paper.

I do not mean to confine myself to the exact details of construction herein disclosed, but claim all variations falling within the purview of the appended claims.

What I claim is:

1. In a device for applying paste to a roll of paper, a hinged paper roll support, adjustable means carried by said support for positioning the paper roll, an adjustable guide for the paper forwardly of said paper roll support, a paste channel, a roller partially immersed in paste in said channel and adapted to apply paste to the paper, a pressure roller for pressing the paper against said first roller, resilient annular ribs on said pres-

sure roller, a guide roller parallel with and spaced from said pressure roller, resilient annular ribs on said guide roller, tensioned means for urging said pressure roller toward said first roller, adjustable spring pressed wipers engaging the ends of said first roller for removing excess paste from the latter, a spring pressed notched wiper engageable with a stretch of paper disposed between said pressure and guide rollers for smoothing the paste, on the paper, a removable paste reservoir, means supporting said reservoir, and a channel connecting said reservoir with said paste channel.

2. A device for applying paste to a strip of paper, comprising a frame, hinged means for holding the strip of paper in a roll at one end of said frame, means adjustable lengthwise of said frame for centering the roll on said hinged means, a pair of guides for the strip of paper forwardly of said roll, a paste trough, a paste applying roller partially immersed in paste in said trough, a pressure roller for pressing the paper against said first roller, annular ribs on said pressure roller, a guide roller parallel with and spaced from said pressure roller, annular ribs on said guide roller, tensioned means for urging said pressure roller toward said first roller, spring pressed wipers engaging the ends of said first roller for removing excess paste from the latter, a spring pressed notched wiper engageable with a stretch of paper disposed between said pressure and said guide rollers for smoothing the paste on the paper, a removable paste reservoir, means supporting said reservoir, and a channel connecting said reservoir with said trough.

3. A device as set forth in claim 2 wherein said reservoir includes a downwardly extending tubular outlet extending into said channel for maintaining a predetermined level of paste in said channel and said trough.

4. A device for applying paste to a strip of paper, comprising a frame, a hinged support for holding the strip of paper in a roll at one end of said frame, discs carried by said frame and said support for centering the roll on said support, a paste trough, a paste applying roller partially immersed in paste in said trough, a pressure roller for pressing the paper against said first roller, resilient ribs on said pressure roller, pivoted lever arms supporting said pressure roller, tensioned means for urging said pressure roller toward said first roller, wipers engaging said ends of said first roller for removing excess paste from the latter, means for adjusting said wipers lengthwise of said first roller, a notched wiper engageable with a stretch of paper disposed behind said pressure roller for smoothing the paste on the paper.
